UNITED STATES PATENT OFFICE.

WARREN J. IDE, OF KINGSTON, PENNSYLVANIA, ASSIGNOR TO THE ADDER MACHINE COMPANY, OF WILKES-BARRE, PENNSYLVANIA, A CORPORATION OF PENNSYLVANIA.

NUMERAL-WHEEL LOCK.

1,095,400.

Specification of Letters Patent. Patented May 5, 1914.

Application filed May 24, 1912. Serial No. 699,581.

To all whom it may concern:

Be it known that I, WARREN J. IDE, a citizen of the United States, residing at Kingston, Luzerne county, Pennsylvania, have invented new and useful Improvements in 5 Numeral-Wheel Locks, of which the following is a specification.

This invention relates to calculating machines of that type wherein the drive members and registering wheels or counters are shiftable relatively one to the other, and more particularly, to means to insure an effective connection between said drive members and counters and to prevent accidental 10 disconnection. Thus, in the well-known Wales type of adding machine, for instance, the counters are held disconnected from the drive members, when the machine is idle. Upon an adding operation, after the drive 15 members have been advanced, the counters drop to engage their pinions with the drive members. In a totaling and clearing, or a sub-totaling operation, the counters drop prior to the advance of the drive members. 20 It has been customary, as illustrated in patent to White, #940,766, dated November 23, 1909, to provide means to hold the pinions firmly in mesh with the drive members, to prevent any rebound of the counters which 25 might result in accidental disconnection from the drive members with a consequent liability of error in the registering operation.

The objects of this invention are to improve and simplify devices of this nature, 30 to make them more compact, and reliable in operation, and to reduce the time required to assemble and adjust the parts thereof.

To these and other ends, the invention 35 comprises certain novel features and combinations, all of which will be more fully disclosed hereinafter, and particularly pointed out in the claims.

In addition to the patent to White, above 40 noted, reference is also made to patent to Wales, #797,032, August 15, 1905, as showing a machine of the type to which this invention may be applied, and in connection with which, it will be illustrated and explained, though the invention is capable of 45 use with other than the Wales machines.

In the accompanying drawings, Figure 1 50 is a view of the left side of a Wales adding machine, showing one embodiment of the

invention applied thereto. Fig. 2 is a sectional view, the machine being idle. Fig. 3 is a side view, showing one of the locking members in effective position, parts being omitted. Fig. 4 is a detail perspective of one of the locking members. Fig. 5 is a detail perspective of one of the axle-supporting arms. Fig. 6 is a side view, similar to Fig. 3, but showing the other of said locking members in operative position. Fig. 7 is a perspective detail of the locking members and co-operating parts, removed from the machine.

Side frames 1 (Figs. 1 and 2) support keyboard and registering mechanisms, the former comprising a series of spring-restituted keys 2, arranged in rows from 1 to 9, if the decimal system is employed. Depression of a key in any row, rocks its respective lever 3 to project a stop 4 above a housing 5, said stops being arranged in rows corresponding to the rows of keys controlling them.

Counters 6 (Fig. 1) are individually rotatable on an axle 7 extending across the machine and mounted at its ends in arms 8 pivoted at 9 to the respective side frames 1. Pinions 10 (Fig. 2) connected to the respective counters, mesh with racks 11 on drive members 12 whereby the counters are turned.

There is a drive member 12 for each counter, said members being supported on forward and rear arms 13 and 14 swinging on a cross shaft 15 and a cross rod 16, respectively, extending across the machine. Drive 90 springs 17 advance the drive members toward the stops. A restraining and restoring bail 18 mounted in arms 19 fixed to rock shaft 20 journaled in the side frames 1, contacts the forward arms 13 to hold the drive 95 members retracted. One end of an arm 21 fixed to the main drive shaft 22 enters a cam slot 23 in a crank 24 fast on the rock shaft 20 to lock the bail against accidental withdrawal.

A counter-shifting mechanism includes props 25, (Fig. 1) connected to the axle-supporting arms 8 at 26, to normally hold the counters elevated in idle position with the pinions 10 out of mesh with their drive 105 members 12.

A trip rod 27 (Figs. 1 and 2) suspended by arms 28 from the cross shaft 15 and held

in position by links 29 connected to arms 30 on the main drive shaft, supports the lower slotted ends of the props.

The main drive shaft 22, when turned in an adding operation, swings arm 21, whose outer end traverses the cam slot 23 to turn the crank 24 and rock shaft 20 to withdraw the bail 18. Springs 17 thereupon advance their respective drive members 12, and swing arms 13, 14 forwardly, until arrested by the projected stops 4 against which the drive members strike, or by detainers 31 (Fig. 2) overlying the stops. Protrusion of the stops 4 by the keys 2 displaces the detainers of the respective rows in which said stops are projected. The detainers overlying rows in which no stops have been displaced, arrest the corresponding drive members, before they have been advanced sufficiently to effect a registration on the corresponding counters. Meanwhile the connecting links 29 have been swinging the trip rod 27 in a descending arc to mesh the pinions 10 with drive members 12. Legs 32 (Fig. 1) depending from arms 8 normally have their feet in line with seats 33 on the side frames and as the trip rod descends, said feet rest on the seats to delay the engagement of the pinions and drive members until the latter have reached their advanced positions. During the initial stroke of the main drive shaft 22, the ends of the trip rod 27 traverse the slots in the lower ends of the props and the slots in bridle links 34 connected to the legs 32, at 35. Toward the end of said initial stroke, the trip rod strikes the ends of the slots in the bridle links and displaces the legs 32 (Fig. 3), whereupon the axle 7 with its supported parts, drops and meshes the pinions 10 with the racks 11, to connect the counters and drive members.

The main drive shaft, on its return stroke, presses the bail 18 against the advanced arms 13 of the drive members to restore the latter; and the drive members, as they retire, turn the counters to register or accumulate an amount corresponding to the values of the keys depressed. The trip rod 27 on such return stroke, at first shifts idly backward, but after the drive members are retired, it quickly swings in an ascending arc to raise the props 25 and disconnect the counters and drive members. Restoring springs 36 (Fig. 1) return the delaying legs 32 to normal position.

Depression of a special clearing key 37 (Fig. 6) rocks set levers 38 fast on cross-shaft 15 and shifts links 39 connecting said levers with the delaying legs 32 to displace the latter relatively to their seats 33. A connection 40 (Fig. 1) between an arm 41 of one of said levers 38 and a connecting bar 42 guided on studs 43, enables the key 37 to shift said connecting bar. A cam face 44 on the bar wipes a crank 45 on a shaft 46, to

which is connected a displacing bail 47 (Fig. 2), to swing said bail and displace the detainers 31. A suitable locking device 48 holds the clearing key depressed during the initial stroke, said locking device preferably being of the type disclosed in patent to McFarland, 842,232, January 29, 1907.

With the parts set as above, the main shaft 22 on its initial stroke, swings the trip rod 27 downwardly to connect the counters 6 and drive members 12 prior to the withdrawal of the restraining and restoring bail 18, so that the drive members turn the counters on their advance, instead of on their retirement, to reverse the direction of rotation of the counters until the latter are reset to their zero positions in a manner well-known in the art and explained, for instance, in patent to McFarland, 842,232, above referred to.

Thrust bars 49, (Fig. 1) pivoted at 50, to counter-restoring levers 51, preferably journaled on the cross-rod 16, normally rest on pins 53 carried by the props 25, and overlie studs 52. These studs rock out from under the bars when the clearing key 37 is set, and on the initial stroke of the main shaft 22, the bars 49 follow the props as they descend until arrested by the studs 52 (Fig. 6).

The locking device 48 partially releases the clearing key 37 at the end of the initial stroke; and at the beginning of the return stroke, springs 54 restore the set levers 38 to normal position. The set levers during their restoration, press the studs 52 against shoulders 55 (Fig. 1) on the thrust bars 49 in the well known manner to force the bars backwardly and rock restoring levers 51, which contact the legs 32 or projections 56 (Fig. 6) thereon, to disconnect the counters from their drive members while the counters remain at zero, and before the retirement of the drive members. The main shaft then causes the restoring bail 18 to retire the drive members and also returns the trip rod 27 and props 25 to normal positions to support the counters in idle position. During the return of the props, the pins 53 thereon, release the thrust bars 49 from the studs 52 to enable the restoring levers 51 to return to normal position out of the paths of the projections 56 on the legs 32, as shown in Fig. 1.

By holding the special key 37 depressed, on the return as well as the initial stroke, the counter-restoring mechanism 49, 51, 32 is prevented from operating, so that the counters and their drive members remain connected, to the end that the amount displayed by the counters prior to the depression of the key 37, and "rolled off" on the initial stroke after the key is depressed, is "rolled back" on the return stroke, and the counters will display the same amount at the end of the operation, as was registered at the commencement thereof. This operation is used in taking sub-totals with a printing mecha-

nism (not shown). Under these conditions, the thrust bars 49 are tripped by pins 53 prior to the restoration of the set levers 38 so that no operation of the counter-restoring levers 51 takes place.

5 The foregoing construction is old and only constitutes part of the present invention in so far as it is combined with the new parts now to be set forth.

10 In operating the machine, the pinions 10 drop suddenly and with some force into mesh with their racks 11, and to hold them in mesh therewith and prevent a rebound which might render the operation inaccurate, I have contrived a simplified and more compact means for locking the counters in effective position. A catch or locking member 57 (Fig. 1) pivoted at 58 to the side frame 1, carries a head 59 confronting a keeper 60 mounted on the axle-supporting arm 8, to fit over said keeper when the pinions drop into mesh with their drive members. A spring 61 (Fig. 3) presses the tail 62 of said catch or a lip or follower 63, 25 thereon, against the rear edge of the adjacent prop 25. The tail, under the influence of its drive spring, follows the prop as the latter is swung forwardly by the trip rod 29 on the initial stroke of the main shaft, 30 in an adding operation, to shift the head 59 toward the keeper 60 against which it finally rests, as the prop continues its advance, so that at the moment the counters drop, with the keeper, toward the end of 35 the initial stroke, the spring snaps the catch over the keeper to hold the counters against a rebound (Fig. 3). The catch and keeper are so positioned relatively to each other that the keeper does not clear the head of 40 the catch to enable the latter to become effective, until the counters have about reached their lower limit of travel.

The catch remains effective during the retirement of the drive members on the 45 turn stroke (at which time the registration of the amount set up on the keys takes place) until the prop on its return, contacts the lip 63 and swings the catch to inactive position against the tension of its drive 50 spring 61. Obviously, the prop must release the catch from the arm 8, or the keeper 60 thereon, prior to the ascent of the trip rod which restores the counters to idle position, but as such ascent occurs at 55 the end of the return stroke, there is time within which to shift the catch the slight distance necessary to release the keeper, after the effective retirement of the drive members and prior to the restoration of the 60 counters, and in any event, the catch may be released as soon as any danger of a rebound is past.

It will be remembered that in taking a total or clearing the machine, the counters drop to effective position with the drive

members at the beginning of the initial stroke, and to hold them effective at that time, I provide a second catch or locking member 64 (Fig. 1) similar to catch 57 and preferably pivoted coincidentally therewith, 70 the head 65 of the catch 64 confronting the keeper 60. The tail 66 of this total or clearing catch, or a stop 67 (Fig. 7) thereon, normally contacts arm 41 of the set lever 38 which holds said catch at rest in the adding 75 or idle operations of the machine. Depression of the controlling key 37 preliminary to a totaling or clearing operation, withdraws said arm 41 of the setting lever and frees the catch to the action of its drive 80 spring 68, which presses the catch 64, or a lug or follower 69 thereon, against the prop 25. On the beginning of the initial stroke, the thrust bar 42 drops until caught on stud 52 and interposes a shoulder or stop 85 70 thereon in the path of the retracted catch 57 or of the lug 63 thereof, to maintain catch 57 substantially idle, throughout the clearing operation.

On the initial stroke, in a totaling and clearing operation, the lug 69 follows the prop 25 to enable the spring 68 to snap the head 65 over the keeper when the counters have reached their limit of travel. Upon the restoration of the key 37 at the end of 90 the initial and the beginning of the return strokes, the set lever 38, in retiring to its normal position, forces its arm 41 against the stop 67 to retract the catch or locking member 64, and thereby enable the trip rod 100 27 to lift the counters to idle position prior to the restoration of the drive members. The arm 41 in returning, presses the thrust bar 49 rearwardly, in restoring the counters. The thrust bar, under such pressure, 105 retracts the item locking member 57 due to the contact of the shoulder or stop 70 with the lug or follower 63. Hence it is immaterial whether the item locking member functions or not during a total or clearing operation, as should it become effective, it will be retired by said shoulder. Preferably, however, the item locking member 57 is held ineffective during a totaling and clearing operation. Obviously the total 110 locking member 64 must be retracted prior to the operation of the restoring lever 51, to permit which, the parts are so arranged that upon the start of the return stroke, the arm 41 immediately shifts the locking member 64, and because of a slight play between the stud 52 on the arm and the shoulder 55, (as exaggerated in Fig. 6 in dotted lines), the catch is retracted prior to the effective operation of the restoring lever 51. 115 Should a sub-total be taken, the operation of the total locking member 64 is the same, except that it is retracted by the prop 25 on its return, which contacts the lug or follower 69. It has been explained that, in a 120 125 130 135

sub-total operation, the set lever 38 is not restored until the end of the return stroke, and hence cannot retire the total catch 64 in sub-totaling operations.

5 The locking mechanism above set forth may be duplicated on the opposite side of the machine from that illustrated.

Changes may be made in the form and arrangement of the several parts disclosed 10 without departing from the spirit and scope of the invention.

What I claim as new is:

1. In a calculator, the combination with 15 registering mechanism, including a gang of counters; drive members with which the counters are connected and disconnected; counter-shifting mechanism to effect such connection and disconnection; and means to control the time of said connection and 20 disconnection, and thus vary the class of operations performed; of a locking member controlled by the counter-shifting mechanism to hold the counters in effective position at the outset of one class of operations 25 of the machine; and a second locking member controlled by the timing means to hold the counters in effective position at the outset of another class of operations of the machine.

30 2. In a calculator, the combination with a registering mechanism including a gang of counters; drive members therefor; counter-shifting mechanism to effect the connection and disconnection of the counters relatively 35 to the drive members; and a clearing mechanism; of a locking member controlled by the clearing mechanism to hold the counters effective when the clearing mechanism is operated; and a second locking member controlled by the counter-shifting mechanism to hold the counters effective at adding operations of the machine.

35 3. In a calculator, the combination with a gang of counters; an axle on which the 45 counters are mounted; arms in which the axle is journaled; drive members for the respective counters; counter-shifting mechanism normally supporting the axle and its counters in idle position, and effective to 50 connect and disconnect the counters and drive members; and a totaling and clearing mechanism; of a locking member to fit over an axle-supporting arm, and normally held idle by the counter-shifting mechanism when 55 the machine is at rest; and a second locking member, controlled by the totaling and clearing mechanism, to fit over said arm and hold the counters and drive members connected at a totaling and clearing operation.

60 4. In a calculator, the combination with a gang of counters; an axle on which the counters are mounted; arms in which the axle is journaled; drive members for the respective counters; counter-shifting mechanism 65 normally supporting the axle and its

counters in idle position and effective to connect and disconnect the counters and drive members; and a totaling and clearing mechanism; of a locking member to fit over an axle-supporting arm and normally held idle 70 by the counter-shifting mechanism when the machine is at rest; a second locking member, controlled by the totaling and clearing mechanism, to fit over said arm and hold the counters and drive members connected 75 at a totaling and clearing operation; and means to arrest the first-named locking member in idle position at a totaling and clearing operation.

5. In a calculator, the combination with 80 registering mechanism, including drive members shiftable in predetermined paths, and counters normally disconnected therefrom; counter-shifting mechanism to effect the connection and disconnection of the counters 85 relatively to the drive members; and mechanism to control the time of connection and disconnection of the counters and drive members; of a locking member controlled by the counter shifting mechanism; and a 90 second locking member controlled by the timing mechanism, said locking members adapted to hold the counters connected with the drive members, at registering and totaling and clearing operations, respectively. 95

6. In a calculator, the combination with registering mechanism, including drive members shiftable in predetermined paths, the counters normally disconnected therefrom; counter-shifting mechanism to effect the 100 connection and disconnection of the counters relatively to the drive members; and mechanism to control the time of connection and disconnection of the counters and drive members; of a locking member controlled by the 105 counter-shifting mechanism; a second locking member controlled by the timing mechanism, said locking members adapted to hold the counters connected with the drive members, at registering, and totaling and clearing operations, respectively; and means to detain the first-named locking member in idle position upon the operation of the second locking member. 110

7. In a calculator, the combination with 115 registering mechanism, including drive members shiftable in predetermined paths, and counters normally disconnected therefrom; and counter-shifting mechanism to effect the connection and disconnection of the counters relatively to the drive members; of separately operable locking members shiftable with the counter-shifting mechanism to hold the counters against disconnection from the drive members; and clearing mechanism to detain one of said locking members against operation until said clearing mechanism is 120 operated.

8. In a calculator, the combination with 125 registering mechanism, including drive 130

members shiftable in predetermined paths, and counters normally disconnected therefrom; and counter-shifting mechanism to effect the connection and disconnection of the counters relatively to the drive members; of 5 separately operable locking members shiftable with the counter-shifting mechanism to hold the counters connected with the drive members; normally idle clearing mechanism to detain one of said locking members against 10 operation until said clearing mechanism is operated; and a stop controlled by said clearing mechanism to arrest the other of said locking members, when the clearing 15 mechanism is operated.

9. In a calculator, the combination with registering mechanism, including drive members shiftable in predetermined paths, and counters normally disconnected therefrom; and counter-shifting mechanism to effect the connection and disconnection of the counters relatively to the drive members; of separately operable locking members shiftable with the counter-shifting mechanism to effective position to hold the 20 counters connected with their drive mechanism; said counter-shifting mechanism effective to restore said locking members to idle position; a totaling and clearing mechanism to normally restrain one of said locking members against operation, and to restore said locking member to idle position after an operation thereof; and a stop 25 effective when the totaling and clearing mechanism to normally restrain one of said locking members against operation, and to restore said locking member to idle position after an operation thereof; and a stop 30 effective when the totaling and clearing mechanism to normally restrain one of said locking members against operation, and to restore said locking member to idle position after an operation thereof; and a stop 35 effective when the totaling and clearing mechanism to normally restrain one of said locking members against operation.

10. In a calculating machine, the combination with a shiftable axle; counters mounted thereon; drive members for the respective counters; and counter-shifting mechanism to effect the connection and disconnection of the counters with the drive members, said counter-shifting mechanism including a prop; of a keeper on the axle; a 40 catch to fit over the keeper to prevent the disconnection of the counters and drive members; and a tail on the catch in the path of the prop to enable the catch to be released for operation and retracted to idle 45 position.

11. In a calculating machine, the combination with a shiftable axle; counters mounted thereon; drive members for the counters; counter-shifting mechanism to effect the connection and disconnection of the counters with their drive members; totaling and clearing mechanism; and counter-restoring means controlled thereby; of a keeper on the axle; a catch to fit over the 50 keeper, said catch normally held ineffective during registering operations, and released for operation and returned to idle position, by the totaling and clearing mechanism.

12. In a calculating machine, the combination with drive members; and counters

shiftable into and out of connection therewith; of a locking member to hold said counters against disconnection from the drive members; a totaling and clearing mechanism to retain said locking member 70 idle in itemizing operations of the machine; and shifting mechanism for the counters, with which the locking member is shiftable to effective position when released by the totaling and clearing mechanism, and by 75 which it is restored to idle position in a sub-totaling operation.

13. In a calculating machine, the combination with a drive member; a counter; means to engage and disengage the drive 80 member and counter; and total and sub-total mechanism for the counter; of a locking member controlled by the engaging and disengaging means to lock the counter and drive member against accidental disconnection 85 during an itemizing operation; a second locking member controlled by the total and sub-total mechanism to lock the counter and drive member against accidental disconnection during a totaling and clearing, or a sub-totaling operation; said totaling and sub-totaling mechanism effective to retain said first-named lock member idle during a totaling and clearing, or a sub-totaling 90 operation; said engaging and disengaging means effective to restore the second-named locking member to idle position during a sub-totaling operation, and to release the first-named locking member from the control of the totaling and sub-totaling mechanism. 100

14. In a calculating machine, the combination with a drive member; and a counter; of locking members; means to engage and disengage the drive member and counter, to 105 release one of said locking members to enable it to lock the drive member and counter against accidental disengagement upon the operation of the engaging and disengaging means; and mechanism to control the time 110 of engagement and disengagement of the counter and drive member, to control the other of said locking members, and to restrain the first-named locking member from operation while the other of said locking 115 members is functioning.

15. In a calculating machine, the combination with a counter; a drive member therefor; means to engage and disengage the drive member and counter; and means 120 to control the time of engagement and disengagement of the counter and drive member; of locking members, one of which locks the counter and drive member against accidental disengagement upon an itemizing operation, when released by the engaging and disengaging means, and the other of which locks the counter and drive member against accidental disengagement, when released by 125 the timing mechanism; said timing mecha- 130

- nism adapted to restrain the first-named locking member against effective operation during the operation of the second-named locking member, and vice versa.
16. In a calculating machine, the combination with a counter; a drive member therefor; means to engage and disengage the drive member and counter; and means to control the time of engagement and disengagement of the counter and drive member; of locking members, one of which locks the counter and drive member against accidental disengagement upon an itemizing operation, when released by the engaging and disengaging means, and the other of which locks the counter and drive member against accidental disengagement, when released by the timing mechanism.
17. In a calculating machine, the combination with a counter; a drive member therefor; means to engage and disengage said counter and drive member; and mechanism to vary the time of engagement and disengagement of said counter and drive member for different classes of operations; of locking members controlled by both said engaging and disengaging means and by said timing mechanism, to enable one or the other of said locking members to lock the counters against accidental disengagement upon any operation.
18. In a calculating machine, the combination with a counter; a drive member therefor; means to engage and disengage the counter and drive member; and mechanism to control the time of engagement and disengagement of said counter and drive member; of locking members controlled by the engaging and disengaging means, and by the timing mechanism, respectively, to lock the counter and drive member against accidental disengagement.
19. In a calculating machine, the combination with a counter; a drive member therefor; means to engage and disengage the counter and drive member; and totaling and sub-totaling mechanism; of separately operable locking members shiftable with the engaging and disengaging means from idle to effective position, to hold the drive member and counter against accidental disconnection; the totaling and sub-totaling mechanism effective to hold either of said locking members idle when the other is released for operation.
20. In a calculating machine, the combination with a counter; a drive member therefor; means to engage and disengage the counter and drive member; and totaling and sub-totaling mechanism; of separately operable locking members shiftable with the engaging and disengaging means from idle to effective position, to hold the drive member and counter against accidental disconnection, said engaging and disengaging means effective to retire the locking members to idle position on itemizing and sub-totaling operations of the machine, the totaling and sub-totaling mechanism effective to hold either of said locking members idle when the other is released for operation, and to retire the active locking member to idle position on a totaling operation of the machine.
